SUBMARINE DETECTION

De Witt R. Goddard, Riverhead, N. Y., assignor
to Radio Corporation of America, a corporation
of Delaware

Application August 30, 1943, Serial No. 500,479

2 Claims. (Cl. 177—386)

1

This invention relates to a new and improved method of submarine detection.

An object of this invention is to provide the means for efficient submarine detection having greater effective range than, as far as I am aware, methods heretofore employed.

Another object of this invention is to produce a simple device to detect the presence of submarines or other submerged objects over great distances.

A feature of this invention is the employment of both high explosive charges to generate sound waves and electrical means to time the echo of the sound returning from the submerged object.

The operation of the invention depends upon the idea of emitting a short pulse or sound in the water close to the boat searching for submarines and electrically recording the echo returning from the submarine.

The range of such equipment as used in the past has been limited due to the fact that electrical devices of limited power have been used to generate the outgoing sounds.

According to my invention I propose to use small charges of high explosive, thereby producing sound pulses in the water of far greater power or amplitude than has been possible in the past, and will result in a greater effective range of submarine detection.

This invention will best be understood by referring to the accompanying drawing in which:

Fig. 1 shows an arrangement for discharging the explosive charges, and

Fig. 2 is a schematic diagram of the electrical recording devices.

Referring now to Fig. 1 of the drawing, a tube or magazine 1 has located therein a plurality of small bombs 2. These small bombs have built within their structure a small time fuse device and detonation arrangement similar to a Mills hand-grenade. The bombs 2 are located in a row within tube 1 and ejected by means of a plunger 3 containing a ratchet portion 6 which is notched to move forward by the pawl arrangement 5 on an armature 4. The armature 4 is driven by the solenoid 8 and movable core 9 which is connected to the armature by means of a link 10. A stop 11 is provided to limit the motion of armature 4 and a spring 12 insures the return of the armature against stop 11. Armature 4 is pivoted at the lower portion by means of a pivot 7. A stop 13 is provided to limit the action of pawl 5.

In the operation of this device, each time that the solenoid 8 is energized the plunger 3 is advanced the correct amount as determined by

2

notches 6 to discharge one bomb from the end of the tube 1. Such a discharged bomb is shown at 14. In the operation of a Mills hand grenade, the time fuse firing the charge is ignited by an explosive cap. This cap is fired by a spring actuated striking piece or hammer which is held in the cocked position away from the cap by means of a hook-shaped piece of metal indicated in Fig. 1 as a detonating lever 15. This lever or hook-shaped piece of metal extends across the top or head of the bomb and along the side of its body as is shown. According to this invention, the detonating lever is retained in this position by the inside wall of the magazine 1. Normally when 15 the hand grenades are used, the force of the hammer would throw off the detonating lever allowing the hammer to strike the explosive cap. However, this is kept from occurring by a suitably placed safety cotter pin and ring (not shown 20 by the drawing). In manual operation, outside of a magazine of this invention, the body of the grenade is grasped in the hand thereby holding the lever against the grenade body in a manner similar to that mentioned above in connection 25 with the magazine. The ring which is attached to the safety cotter pin is previously taken out. In this manual operation, the only thing keeping the detonating lever from flying off is the hand of the operator. When the grenade is 30 thrown, the force released causes the detonating lever to fly off allowing the hammer to strike the explosive cap and a few seconds after the fuse has burned its full length, the grenade explodes. As mentioned above, these bombs are built with 35 a detonating arrangement which requires the lever 15 to be released. The release of lever 15 is accomplished by holding the detonating lever 15 against the body of the bomb and removing the safety cotter pin. Then the bomb is pushed 40 into the forward end of the magazine 1. The bore of the magazine being of a suitable diameter, keeps the lever 15 against the body of the bomb. However, when the bomb is pushed out from the discharge end of the magazine and drops 45 as indicated at 14, in Fig. 1, the detonating lever 15 flies off as indicated at 16, thereby permitting the explosive cap striking mechanism to function as mentioned above. This release will occur at the moment the bomb leaves the inside of the 50 magazine tube as shown at 16. The magazine tube is positioned to extend over the stern of the boat so that the bombs will drop in the water. A few seconds later the fuse discharges the bomb which in the meantime has sunk a few fathoms 55 below the surface. The resulting high-intensity

sound wave travels radially in all directions through the water. The sound wave is then picked up on a recording device 26 shown in Fig. 2 on board the ship, and provides a reference from which the time delay may be determined. From this reference, the distance traveled by the sound waves and its reoccurring echoes may be determined.

In Fig. 2 the bomb discharger is shown as being electrically connected to an electrical timer 21 having a hand release button 22, a bell 23 and pickup devices 24 and 25. The timer periodically starts rotation of the recorder and also discharges a bomb into the water. The resulting explosion is picked up by the two pickup microphones 24-25 which may be located near the bow and stern of the boat respectively. These microphones record a mark on the recorder 20. Echoes from submerged objects are also picked up by the microphones and make their marks on the recorder 20 chart. By knowing the recorder chart speed and measuring the distance between the initial mark and the subsequent marks due to echoes, the distance and bearing of submerged objects within the range of the apparatus may be ascertained. There are, of course, two possible bearings for each set of data obtained, but this ambiguity may be removed by changing the course of the ship slightly and through the use of hand release button 22 discharging another bomb.

The bell rings each time a bomb is discharged so as to attract the attention of the man on watch in order that he may inspect the chart for suspicious echoes.

While I have indicated and described a system of my invention, it will be apparent to one skilled in the art that my invention is by no means limited to the particular devices shown and described, but that many modifications may be made without departing from the scope of my invention.

What I claim is:

1. A system for locating submerged objects comprising a tubular magazine containing a plurality of bombs of the type having an explosive time fuse detonating lever, each one of said bombs being arranged in a row within said tubular

magazine so that the release lever is retained inoperative thereby, a plunger rod having a plurality of ratchet portions for periodically ejecting one of said bombs and releasing said lever so that the bomb is automatically detonated a predetermined short time interval after ejection, a pivoted armature and an electromagnet, said armature being linked to said plunger rod and forming a part of a timing system for periodically actuating said plunger when said electromagnet is energised, a spring actuated pawl pivoted on said armature for providing forward movement of said plunger, a recording device electrically connected to said timing system, a pick-up device electrically connected to said recording device whereby the distance of submerged objects can be determined by measuring the elapsed time between the exploding of said ejected bomb and the returning echoes.

2. A system for locating submerged objects including a tubular magazine containing a plurality of bombs of the type having an explosive time fuse detonating lever, each one of said bombs being successively arranged within said magazine so that the detonating lever is retained inoperative thereby, a plunger rod having one end extending within said tubular magazine, said plunger having a plurality of ratchet portions for periodically ejecting one of said bombs and thereby releasing said detonating lever so that the bomb automatically detonates a predetermined short time interval after ejection, a pivoted armature linked to said plunger rod, a pawl pivoted to said armature and arranged to engage the ratchet portion of said plunger rod, an electric solenoid, a movable core located within said solenoid and linked to said armature and forming part of a timing system, electric means associated with said timing system for periodically energising said solenoid for actuating said armature to eject one of said bombs, a recording device and a plurality of pick-up devices electrically connected to said electric means whereby the distance of submerged objects can be determined by measuring the elapsed time between the explosion of said ejected bomb and the returning echoes.

DE WITT R. GODDARD.
